UNITED STATES PATENT OFFICE

HARRIE A. BALLARD, OF BEVERLY, MASSACHUSETTS, ASSIGNOR TO UNITED SHOE MACHINERY CORPORATION, OF PATERSON, NEW JERSEY, A CORPORATION OF NEW JERSEY

HEEL-SEAT FITTING MACHINE

Application filed June 22, 1928. Serial No. 287,430.

This invention relates to heel-seat fitting machines and is illustrated herein as embodied in a power-operated machine adapted to perform the heel-seat fitting operation upon shoes which are to receive wood heels of any of the types now in general use.

In the manufacture of shoes having wood heels, it is usual, after a sole has been attached to a shoe by stitching extending from one end of the heel breast line forwardly around the toe of the shoe and back on the other side of the shoe to the other end of the heel breast line, to trim the surplus material from the periphery of the heel-seat portion 15 of the sole, at the same time beveling the sole to conform to the concave attaching surface of a wood heel, and forming a transversely extending heel breast receiving abutment in the sole at its heel breast line. In the case 20 of shoes to which Cuban heels, or other heels having substantially straight breasts, are to be attached, this abutment usually takes the form of two separate shoulders cut in the sole at opposite ends of the heel breast line 25 and spaced apart by the uncut median portion of the sole. These shoulders are inclined transversely relatively to the median line of the sole to conform to the transverse curvature of the breast of a Cuban heel. A 30 method often used in forming the abutment to receive the forwardly projecting portion of the breast of a Louis heel is to form a flap in the sole by a cut extending transversely across the sole from one edge to the other 35 and inclined only slightly relatively to the tread surface of the sole, the flap thus having a relatively thick base at or just forward of the heel breast line and tapering rearwardly to a thin edge which overlies the breast of 40 the heel.

Machines have been in operation in this country for some years adapted to trim surplus material from and to bevel the periphery of the heel-seat portions of shoes to prepare the shoes for the attachment of wood heels and to form the transversely extending flap just referred to which is frequently used as an abutment in shoes to which Louis heels are to be attached. A machine of this character which has gone into extensive use is

disclosed in Letters Patent of the United States No. 1,661,391, granted March 6, 1928, on an application filed in the name of William C. Stewart. While these machines have been highly successful for Louis heel work, when it is desired to use them for Cuban heel work it is necessary, after the sole has been trimmed and beveled by the machine, to form the heel breast receiving abutment by hand.

It is, accordingly, an object of the present invention to provide an improved heel-seat fitting machine adapted to perform the complete heel-seat fitting operation upon shoes to which any type of wood heels are to be attached.

A feature of the invention comprises the combination in a heel-seat fitting machine of a cutter movable transversely across the sole of a shoe at the heel breast line of the sole 70 to form a heel breast receiving abutment in the sole and means for moving the cutter heightwise of the shoe to vary the depth to which the cutter operates on the sole of the shoe. Preferably and as illustrated, the 75 cutter, as it enters the edge of the sole, cuts through the whole thickness of the sole but is moved heightwise of the shoe so that it passes out of the sole before it reaches the median line of the shoe. Then, after the 80 cutter has passed the median line of the shoe, it enters the tread surface of the sole, finally cutting through the entire thickness of the sole before the other edge of the sole is reached. This cutter, moreover, in order to 85 adapt it for work upon shoes to which Cuban heels are to be attached, is arranged, in accordance with still another feature of the invention, to enter and to leave the sole in a path inclined relatively to the median line 90 of the sole so that the abutment formed by the cutter will correspond in shape to the transverse curvature of the breast of a Cuban heel. In the illustrated machine the cutter is carried by a shaft extending heightwise of the 95 shoe to be operated upon and positioned forwardly of the heel breast line of the sole of the shoe. The cutter is attached to an arm projecting from the shaft and, as the shaft is rocked, sweeps across the sole of the shoe 100

in a curved path to form a heel breast receiving abutment at the breast line of the sole.

In accordance with a further feature of the invention, and to render the machine applicable to all kinds of heel-seat fitting work, the illustrated machine is provided with two abutment forming cutters alternatively operable, one to form a heel breast 10 receiving abutment in the form of a pair of separate shoulders inclined relatively to the tread surface of the sole only sufficiently to aline them vertically with the breast of a Cuban heel and the other of which is inclined 15 at a small angle to the tread surface of the sole of the shoe operated upon so as to form a tapered flap for the reception of the breast of a Louis heel.

The heel-seat fitting machines which have 20 been used prior to my invention have substantially increased the output of the operator as compared to the performance of the operation manually. Nevertheless, these machines have been relatively slow since in the 25 best of them the movement of the trimming cutter peripherally of the heel-seat of the sole of a shoe was manual. It is another object of the present invention to speed up the operation and this is done in the illustrated machine, in accordance with a feature 30 of the invention, by moving the trimming cutter which removes surplus material from and bevels the heel-seat portion of the sole of a shoe, as well as the cutter which forms the heel breast receiving abutment, by power. This is effective both to relieve the 35 operator of the labor of forcing these cutters through the relatively hard and tough leather of the sole of the shoe operated upon and, as stated above, to speed up the operation.

In accordance with a further feature of the invention, the cutter which trims the surplus material from the periphery of the heel-seat portion of the sole is guided in a path 45 extending peripherally of the heel-seat by a guide, illustrated as a groove formed in and parallel to the edge of crease plates which enter the rand crease of the shoe to be operated upon. In the illustrated machine, this 50 cutter takes the form of a drag-knife having a cutting edge inclined relatively to the top of the crease plates and to the tread surface of the sole of the shoe.

A further feature of the invention comprises an improved combination of a hold-down member or members and a cutter or cutters whereby displacement of the heel-seat portion of the sole of a shoe by the cutter or cutters is avoided. This overcomes one of 60 the principal difficulties heretofore met with in attempting to perform the heel-seat fitting operation by machine on welt or McKay shoes the heel-seat portions of which are not ordinarily attached with any degree of security 65 prior to the performance of the heel-

seat fitting operation. The provision of this holdown member or members does not in any way interfere with the operation of the machine upon turn shoes having sewed heel-seats and, indeed, is of some assistance even 70 under those circumstances since the shoe is held more firmly than it otherwise would be.

Some wood heels are made unsymmetrical, extending further forward on the outer edge than upon the inner edge. That is to say, the 75 heel breast line, considered as a whole, is inclined forwardly toward the right on the heel of a right shoe and toward the left on the heel of a left shoe. It is, accordingly, a further object of the invention to provide 80 means for so positioning a shoe to be operated upon by the machine that the trimming operation may be extended somewhat further forward on the right side of a right shoe and on the left side of a left shoe than on the 85 left side of a right shoe and on the right side of a left shoe. The illustrated machine is provided with a pair of side gages movable widthwise of the shoe, both in the same direction, to vary the transverse position of the 90 shoe in the machine relatively to the path of movement of the trimming cutter and the abutment-forming cutters according as the shoe to be operated upon is a right or a left shoe. 95

In this specification and claims the words "Cuban heel" are to be taken as designating any heel having a straight or substantially straight breast, in contra-distinction to Louis heels, rather than as applicable only to Cuban 100 heels in the strict sense of the term. They are to be taken as covering not only Cuban heels in the strict sense but also other heels of that general nature, low flat heels having substantially straight breasts, and even semi-Louis 105 heels the breasts of which are curved to a considerable extent but which lack the forwardly projecting overhanging portion characteristic of full Louis heels.

With the above and other objects and features in view, the invention will now be described with reference to the accompanying drawings, which illustrate a preferred embodiment of the invention, and pointed out in the claims. 115

In the drawings,

Fig. 3 is a perspective view, partly in section, of a latch mechanism a portion of which is shown also in Fig. 2;

Fig. 4 is a side elevation of the head and treadle mechanism of the machine of Fig. 1; 125

Fig. 5 is a perspective view of rand crease entering plates of the machine, together with a cutter which is operative to trim surplus material from and to bevel the periphery of 130

the heel-seat portion of the sole of a shoe, and showing the cutter and cutter carrier in inoperative position;

5 Fig. 6 is a plan view of the head of the machine, certain parts being broken away and other parts being shown in section;

10 Fig. 7 is a diagrammatic view of gage mechanism with which the machine is provided to position the shoe to be operated upon;

15 Fig. 8 is a perspective view, partly in section, of dial mechanism which is provided to adjust the abutment cutter lengthwise of the shoe to be operated upon;

20 Fig. 9 is a longitudinal section of the lower, right-hand portion of the head of the machine;

25 Fig. 10 is a plan view of a portion of the adjusting mechanism by means of which the forward extent of the beveling and trimming cut formed in the sole of the shoe is varied;

30 Fig. 11 is a diagrammatic view of portions of the mechanism of Fig. 10;

35 Fig. 12 is a perspective view of the heel-seat portion of a shoe in the sole of which a heel breast receiving abutment has been formed by the illustrated machine, the trimming knife which is utilized to trim surplus material from and to bevel the periphery of the heel-seat portion of the sole, and a hold-down member adjacent to the knife being shown in the position which they occupy at the start of the trimming and beveling cut; and

40 Fig. 13 is a view of the heel-seat portion of the shoe of Fig. 12 after the completion of the heel-seat fitting operation by the machine.

45 The illustrated heel-seat fitting machine is provided with a column 16, the major portion of which is broken away in the drawings, at the top of which is carried a stationary head 18 provided with a horizontal table 20 having toward its right-hand side forwardly and rearwardly extending ways 22 (Fig. 6) in which a movable head 24 (Figs. 1, 2 and 6) is mounted for forward and rearward sliding adjustment, carrying with it the means for forming heel breast receiving abutments in the soles of shoes presented to the machine. 50 A stationary bracket 26 extends upwardly from the table 20 to the rear of the movable head 24 and is provided with a threaded opening receiving a screw 30 for adjusting the movable head 24. The head of the screw 30 is provided with a hand wheel 32 and a dial portion 34 (Figs. 6 and 8).

55 The screw 30 has a bearing arranged axially in a larger screw 36 threaded, as shown at 38, into the movable head 24. The dial 34 of the screw 30 and a collar 40 pinned to the screw 30 at the rear end of the screw 36 serve to prevent relative axial movement of the screws 30 and 36. At its head end the larger screw 36 is provided with a hand wheel and dial 42, the dials 34 and 42 co-operating with

an index finger 44 carried by the movable head 24 adjacent to the dials. The index finger 44 may be graduated, if desired, to indicate the longitudinal as well as the rotary adjustment of the two dials. A bushing 46 surrounds the forward unthreaded portion of the screw 36 and is restrained against longitudinal movement relatively to the screw by the dial 42 and a collar 48 secured to the screw 36.

70 A spring-pressed plunger 50 (Fig. 8) housed in a bore formed in the movable head 24 passes through a slot 52 in the bushing 46 and has a conical end normally engaging one or another of a plurality of shallow grooves 54 formed in the non-threaded surface of the screw 36, thus tending impositively to restrain the screw 36 against rotation and being effective to prevent rotation of the screw 36 when the hand wheel 32 and the screw 30 are rotated. A collar 56 secured to the rear end of the screw 30 limits the movement of that screw in a forward direction by engagement with the bracket 26 while the collar 40 limits the movement of the screw rearwardly in a similar fashion.

75 Thus it will be seen that when the hand wheel 32 is rotated, the screw 30, because of its threaded engagement with the bracket 26, is effective to slide the movable head 24 forwardly or rearwardly as the case may be relatively to the plate 20, the screw 36 moving lengthwise with the screw 30 but not rotating. On the other hand, when the dial 42 is rotated, the screw 36 turns on the non-threaded portion of the screw 30 but does not move axially, sliding the movable head 24 forwardly or rearwardly by reason of its threaded engagement therewith.

80 As already stated, the movable head 24 in the illustrated machine is provided with means for forming heel breast receiving abutments in the soles of shoes operated upon and the position of the abutment lengthwise of the shoe is determined by the position of the movable head 24. The graduations of the dial 34 are such that rotation of the dial the distance between two graduations slides the movable head 24 an amount equal to the difference in length between one size of heel 85 and the next adjacent size of the same style of heel, regardless of what that particular style may be. The dial 42, on the other hand, is used to adjust the movable head 24 to compensate for variations in the length of the 90 heels of different styles but of the same nominal size. Thus the head 24 will be moved further forward when operating upon a shoe to which a Louis heel is to be attached than it will be when operating on a shoe of the 95 same size to which a Cuban heel is to be attached. The adjustment of the movable head 24 is also effective to control the forward extent of the path of movement of a trimming cutter, hereinafter described, which 100

is utilized to trim surplus material from and to bevel the periphery of the heel-seat portion of the sole of a shoe presented to the machine.

5 The left-hand forward portion of the plate 20 is recessed and provided with a seat 60 (Fig. 1) in the form of an arc illustrated as of about 270 degrees and arranged to receive a pair of crease plates 62, 64 (but shown in 10 Figs. 1, 5 and 6) having a corresponding outline and arranged for arcuate adjustment about the center of the seat 60. The inner edges of these crease plates have an approximately horseshoe-shaped form and are reduced, as shown at 68 (Fig. 5), to enter the rand crease of a shoe presented to the machine. Each crease plate is provided, parallel to its edges 68, with a groove 70, the vertical walls of which form a guide for a pair of rolls 72 (Figs. 5 and 6) depending from the lower surface of a cutter carrier 74 to which is also secured a knife 76 arranged for movement, under the control of the guide groove 70, peripherally of the heel-seat portion of the sole of a shoe the rand crease of which is engaged by the edges 68 of the crease plates 62, 64 to trim surplus material from and to bevel the periphery of the heel-seat portion of the sole as will be hereinafter described.

20 Co-operating with the crease plates 62, 64 to hold a shoe which is to be operated upon is a work support 80 terminating in a last pin 82 (Figs. 2 and 9) mounted in a slide 84 for transverse movement relatively to the upper end of a tubular outer member 86 of the work support 80. The tube 86 is telescopically mounted on a rod 90 pivoted at 92 (Figs. 2 and 4) to a bracket 94 attached to the head 25 18 of the machine. A spring 91 (Fig. 2), housed within the tube 86 and bearing at its lower end against the upper end of the rod 90, tends to raise the tube 86 of the work support 80, and the shoe carried thereby, relative movement of the rod 90 and the tube 86 being limited by a pin 93 at the lower end of the tube 86 and engaging a slot 95 formed in the rod 90, as shown in Fig. 2. Also pivoted at 92 to the bracket 94 is a pair of cams 50 96 the upper edges of which are engaged by a pair of rolls 98 carried by the lower end of the tube 86 (Figs. 1, 4 and 9).

55 It will be seen that rearward or clockwise movement of the cams 96, as viewed in Fig. 4, is effective to raise the work support 80. A rearwardly extending link 100 is pivoted at 102 to the cams 96 (Figs. 4 and 9) and is provided at its rear end with a slot 104 through which passes a pin 106 carried by the lower end of the depending arm of a three-armed lever 108. The lever 108 has a 60 forwardly extending arm provided with a hand grip 110 by means of which the lever can be rocked about its fulcrum 112. A pawl 65 114 carried by the lever 108 and manipulated

by a supplemental lever 116 fulcrumed to the rear end of the hand grip 110 co-operates with a ratchet 118 fast to the frame 18 of the machine to hold the lever 108 in adjusted position. A spring 120, fast at one end to the pin 106 and at the other end to an adjustable screw 122 carried by the forward end of the link 100, forms an operative connection between the lever 108 and the cams 96 so that downward movement of the hand grip 110 serves impositively to rotate the cams 96 in a direction to raise the work support 80 and a shoe mounted upon a last carried thereby, while upward movement of the hand grip 110 serves positively to rotate the cams 96 in the opposite direction, to permit the work support to be lowered. As this is done, the operator moves the work support 80 forwardly removing the shoe from the crease plates 62, 64, and this he can do without difficulty by reason of the presence of the spring 120 and the pin and slot connection 104, 106.

70 The detail of construction of this work supporting mechanism is not claimed in this application since it forms the subject-matter of 80 my co-pending application Serial No. 170,881, filed February 25, 1927, for improvements in Heel-seat fitting machines.

75 The position of the crease plates 62, 64 in the seat 60 is adjusted by movement of the lever 108 (Figs. 4 and 9) since that lever is provided with an upwardly extending arm 130, the upper end of which is pivoted at 132 to a horizontal, transversely extending lever 134 fulcrumed at 136 to the plate 20, as shown in dotted lines in Fig. 6. The median portion of the lever 134 is connected by a pair of links 138 with the crease plates 62 so that downward movement of the hand grip 110 moves the forward portions of the crease plates 62, 64 toward each other, narrowing the spread of the horseshoe-shaped rand crease entering edges 68 of the crease plates.

80 The upper end of the movable head 24 is provided with an arm 140 extending to the left, as shown in Figs. 1 and 2, and provided near its end with a vertical slideway 142 in which is mounted a slide 144 normally held in elevated position by a bell crank lever 146 fulcrumed at 148 to the movable head 24 and urged in a clockwise direction, as viewed in Fig. 2, by a spring 152 secured at one end to the depending arm of the bell crank lever 146 and at the other end to the arm 140. A pin 154, projecting forwardly from the slide 144, is positioned above and engages the approximately horizontally extending arm of the bell crank lever 146. A stop screw 156 is adjustably carried by the slide 144 and engages a shoulder 158 carried at the rear of the arm 140 to limit downward movement of the slide 142 under the influence of mechanism which will now be described.

85 115 120 125 130 A treadle 160 (Fig. 4) is fulcrumed at 162

near the base of the column 16 and is connected by a rod 164 with a lever 166 fulcrumed at 168 to the bracket 26 and extending toward the left, as best shown in Figs. 1 and 2. Mounted for sliding movement lengthwise of the lever 166 is a rod 170 urged toward the left by a spring 172 secured at one end to the rod 170 and at the other end to the lever 166. When the rod 170 is moved to the left by the spring 172, its left-hand end is positioned above a roll 174 carried by a pin 176 extending rearwardly from the slide 144, as shown in Figs. 1 and 2. With the parts in this position, it will be seen that depression of the treadle 160 is effective to rock the lever 166 in a clockwise direction, thus forcing the slide 144 downwardly until the lower end of the screw 156 engages the shoulder 158 of the arm 140.

5 10 15 20 25 30 35 40 45 50 55 60 65

Mounted for vertical sliding movement in ways formed at the rear of the left-hand end of the arm 140 is a holdown member 180 (Fig. 2) in the upper portion of which is formed a sleeve 182 surrounding a rod 184 attached by a link 186 to the left-hand end of the lever 166, as shown at 188. A spring 189 is housed within the sleeve 182 and provides a yieldable connection between the sleeve 182 and the rod 184 so that when the central part of the heel-seat portion of a shoe carried by the work support and the rand crease of which has been entered by the crease plate 62 is engaged by the holdown member 180, further downward movement of the left-hand end of the lever 166 will do no damage. Carried at the lower end of the slide 142 are a pair of spring-pressed holdown members 190 arranged to engage the sole of the shoe just forward of the ends of its heel breast line. These three holdown members are effective to prevent the displacement of the heel-seat portion of the sole of a shoe while the heel-seat fitting operation is being performed, even though the sole attaching means does not extend rearwardly of the heel breast line, as is commonly the case in the manufacture of McKay and Goodyear welt shoes and in the manufacture of some turned shoes.

70 75 80 85 90 95 100 105 110 115 120 125 130

A vertical rock shaft 200 is journaled in the slide 144 and is provided at its lower end with an arm 202 to which is secured a cutter 204 illustrated as a knife having a channel-shaped cutting edge (Fig. 2). The shaft 200 is positioned about two inches forwardly of the heel breast line of the sole of a shoe to be operated upon so that as the shaft 200 is rocked the knife 204 will be moved transversely across the sole of a shoe positioned in the machine, at the heel breast line of the sole, so that the forward, approximately vertical, cutting edge of the knife 204 will cut a heel breast receiving abutment in the sole while the horizontal portion of the cutting edge and the upturned portion at the rear will sever a chip from the sole leaving a groove in the sole $\frac{1}{16}$ of an inch more or less wide. In order that the abutment may consist of two portions separated by the uncut median portion of the sole, as is commonly desired in performing the heel-seat fitting operation upon shoes to which Cuban heels are to be attached, a cam 210 (Figs. 1 and 2) is carried by the slide 144 and a cam roll 212 carried by an arm 214 pinned to the shaft 200 is held in engagement with the cam 210 by a spring 216 surrounding the shaft 200 and bearing at its upper end against an abutment 218 carried by the slide 144 and at its lower end against a collar 220 secured to the shaft 200. The cam 210 is of such a formation that the cutter 204, when it enters the sole at the right, cuts through the entire thickness of the sole but is gradually lifted, passing out of the tread surface of the sole before the median line of the sole is reached; then, after the median line has been passed, the cutter 204 is moved downwardly into engagement with the tread surface of the sole, cuts into the sole and finally, before it passes out at the further edge of the sole, cuts through the entire thickness of the sole, thus providing an abutment of the character shown at 224 in the sole 226 of the shoe 228 illustrated in Figs. 12 and 13, which abutment, it will be noticed, is formed in two separate portions each of which is inclined relatively to the median line of the shoe to correspond with the transverse curvature of the breast of a Cuban heel.

When the slide 144 and the holdown member 180 are moved downwardly by the depression of the treadle 160, they are held in that position by reason of the fact that the treadle 160 is latched in depressed position by the engagement of a dog 230 (Fig. 4), fulcrumed at 232 to the treadle 160, beneath a latch plate 234 carried by the column 16 of the machine and the parts are held latched in this way until after the heel breast receiving abutment has been cut.

The shaft 200 is provided with a pinion or gear segment 235 engaging a rack bar 236 mounted for horizontal movement in the slide 144, the left-hand end of the bar 236 contacting with a depending lever 238 fulcrumed at 240 to the top of the slide 144 and urged in a counterclockwise direction, as viewed in Figs. 1 and 2, by a spring 242 secured at one end to the lever 238 and at the other end to the slide 144. Thus it will be seen that movement of the rack bar 236 to the left is effective to operate the knife 204 to form a heel breast receiving abutment in the sole of a shoe presented to the machine while the knife 204 will be returned to its normal position at the conclusion of the operation by the spring 242.

The mechanism for moving the rack bar 236 to the left comprises a single revolution clutch 250 which may be of any convenient

type. The clutch 250 has a continuously rotated member 251 (Figs. 4 and 6) splined on a shaft 253 driven from a shaft 255 by spiral gears 257. The shaft 255 carries a worm wheel 259 driven from a worm 261 mounted upon the rotor shaft of a motor 263.

The clutch member 251 may be moved lengthwise of the shaft 253 by the depression of a hand lever 252 positioned at the right-hand side of the machine, best shown in Figs. 1 and 4. This causes the clutch to transmit power to a crank disk 254, rotating the crank disk through a single revolution. The crank disk 254 is provided with a crank pin 256 (Fig. 2) to which is pivoted a connecting rod 258 extending to the left and terminating in a horizontal forwardly extending pin 260 normally positioned at the left-hand end of a slot 262 formed in a slide bar 264 mounted for transverse movement to the left in a guideway formed in the movable head 24. The pin 260 is of such a length that the operation of the bar 256 is in no way interfered with by forward and rearward adjustment of the movable head 24. At its forward end the slide bar 264 is provided with an upwardly extending plate 266 which, while the machine is at rest and the slide 144 is in its lowered position, is in horizontal alignment with and closely adjacent to the right-hand end of the rack bar 236. Thus depression of the hand lever 252 is effective to move the rack bar 236 to the left and to cause the cutter 204 to form the heel breast receiving abutment in the sole of a shoe. A spring 280, secured at its right-hand end to a pin 282 carried by an extension of the connecting rod 258 and at its left-hand end to the slide bar 264, is effective to return the slide bar to the position shown in Figs. 1 and 2 at the conclusion of the operation.

After the heel breast receiving abutment has been formed but before the surplus material has been trimmed from the periphery of the heel-seat portion of the sole of a shoe, the slide 144 is raised to the position shown in Fig. 2, the holddown member 180, however, being maintained in engagement with the sole of the shoe. This is permitted by longitudinal movement of the rod 170 while the lever 166 is maintained latched in its depressed position by the dog 230. For this purpose a lever 290 is fulcrumed at 292 to the movable head 24 with its upper end extending somewhat above and to the left of a forwardly projecting finger 294 carried at the right-hand end of the rod 170. A spring-pressed latch 296 (Fig. 3), housed in the lever 166 near its fulcrum is arranged for engagement with a shoulder 298 formed in the rod 170 so that when the lever 290 is rocked through a small angle in a clockwise direction, as viewed in Figs. 1 and 2, the rod 170 will be moved to the right and latched in that position by the latch 296. This move-

ment of the rod 170 to the right causes the left-hand end of the rod to pass out of engagement with the roll 174 of the slide 144 so that the latter can move upwardly which it does under force applied by the spring 152.

The latch member 296 is slidably mounted in a sleeve 297 carried by the lever 166. A spring 299, bearing at one end against a block 301 screwed into the sleeve and at the other end against the latch member 296, tends to move the latter forwardly while another spring 303, surrounding the sleeve and bearing at one end against a collar 305 formed on the rear of the sleeve 297 and at the other end against a shoulder 307 formed in the lever 166 and surrounding the sleeve 297, tends to move the sleeve 297 rearwardly. The collar 305 at the rear of the sleeve 297 is provided with a beveled surface 309 arranged, when the lever 166 is rocked in a counterclockwise direction from the position in Fig. 2, to engage an inclined surface 311 formed on the bracket 26 so that the sleeve 297 is thrust forwardly bringing the latch member 296 into operative position so that it may be effective to engage the rod 170 when the latter is moved to the right to bring its shoulder 298 into alignment with the latch member 296. On the other hand, when the lever 166 is swung upwardly to the position shown in Fig. 2, the spring 303 will move the collar 305 rearwardly withdrawing the latch member 296 and rendering it inoperative. A projection 313 formed on the sleeve 297 engages a flat surface 315 at the front end of the latch member 296, limiting forward movement of the latch member in the sleeve 297.

In order to rock the lever 290, its median portion is connected by a link 300 with a depending lever 302 the upper end of which is provided with a slot 304 through which passes a fulcrum pin 306 carried by the movable head 24. The lower end of the lever 302 engages the upper surface of the slide bar 264 in which surface is provided a notch 308 which the lower end of the lever 302 enters when the slide bar 264 moves to the left so that, as the slide bar 264 is returned toward the right, the lever 302 is rocked through a small angle in a counterclockwise direction (as viewed in Figs. 1 and 3) thus rocking the lever 290 in a clockwise direction and withdrawing the rod 170 from the roll 174. The rod 170 is latched in this withdrawn position by the latch 296. Before the slide bar 264 has reached its normal inoperative position, as shown in Fig. 2, the rotation of the lever 302 lifts the lower end of that lever out of the notch 308 and a spring 310, anchored at one end to the movable head 24 and at the other end to the lever 302, returns the lever to substantially the position shown in Fig. 2.

If, instead of fitting the shoe to be operated upon for the reception of a Cuban heel,

it is desired to fit the shoe for a Louis heel by cutting from the sole a tapered flap beneath which the forwardly projecting portion of the heel breast may be positioned, the operation of the machine is somewhat different. When the machine is to be operated in this manner, the lever 290 is rocked a few degrees in a clockwise direction, as viewed in Figs. 1 and 2, by the rotation through 180 degrees of a manually adjustable cam or eccentric 320 provided with a handle 322 by which it may be moved. This moves the rod 170 to the right and holds it in that position. Adjustment of the eccentric 320 is also effective to rock, in a clockwise direction, a lever 324 also fulcrumed at 292 to the movable head 24 and urged in a counterclockwise direction, as viewed in Figs. 1 and 2, by a spring 326. Below its fulcrum the lever 324 is provided with a slot engaging a pin 328 carried by an upwardly extending arm of a bell crank lever 330 provided also with a horizontally extending arm from which a finger 332 extends forwardly into a notch 334 formed in the upper end of a plunger 336 mounted for endwise sliding movement in a lever 338 loose upon the shaft 340 to which is pinned a rock arm 342 having in its upper end a notch formed to receive the lower end of the plunger 336 when the latter is depressed by clockwise movement of the lever 330. The lever 338 is normally held in engagement with a pin 343 by a spring 345 (Fig. 1). The latch mechanism, indicated at 344, which may comprise a spring-pressed ball arranged to enter one of two depressions formed in the plunger 336, serves impositively to hold the plunger 336 either in its elevated, inoperative position, shown in Figs. 1 and 2, or in its lower position in which its lower end enters the notch of the rock arm 342. Also pinned to the rock arm 342 is a second arm 346 to the end of which is secured a downwardly extending link 348 connected to the treadle rod 164 (Fig. 2). Thus, if the eccentric 320 is rocked 180 degrees from the position shown in Figs. 1 and 2, depression of the treadle 160 will be effective to rock the lever 338 in a counterclockwise direction, as viewed in Figs. 1 and 2. The upper end of the lever 338 is connected by a link 350 to a lever 352 fulcrumed to the movable head 24 of the machine and provided at its upper end with a pin 354 (Figs. 1, 4 and 6) extending beyond the end 55 of the slide bar 264 and closely adjacent thereto, so as to move the slide bar to the left when the lever 352 is rocked. When this takes place, the right-hand end of the slot 262 moves into engagement with the pin 260 of the connecting rod 258 and the pin 260 drops into a depending portion 356 with which the right-hand end of the slot 262 is provided. When operating the machine in this manner it is not desired to utilize the holdown members 180, 190 nor the cutter 204. Accord-

ingly, a supplemental treadle 360 is fulcrumed at 362 to the treadle 160, the treadle 360 carrying at its rear end a cam roll 364 engaging a cam surface with which the dog 230 is provided, the arrangement being such that depression of the treadle 360 relatively to the treadle 160 rocks the dog 230 out of engagement with the plate 234 against the tension of a spring 366 secured at one end to the dog 230 and at the other end to the treadle 160, and normally tending to urge the dog 230 into engagement with the plate 234. If the foot is placed upon the supplement treadle 360 as well as the treadle 160 when the latter is depressed to move the slide bar 264 so as to bring the pin 260 into the depending portion 356 of the slot 262, then when the foot is removed the lever 166 will move upwardly to the position shown in Figs. 1 and 2, removing the holdown members 180 from the heel-seat portion of the sole of the shoe. The slide 144, which carries the cutter 204 and the holdown members 190 will not have been lowered since the rod 170 was held by the lever 290 too far to the right to engage with the roll 174.

The slide bar 264 serves also as a carrier for a knife or cutter 370, best shown in Fig. 2, having a straight cutting edge an inch or more wide and extending lengthwise of the shoe but somewhat inclined relatively to the tread surface of the sole of the shoe, as more fully disclosed in Letters Patent of the United States No. 1,661,391, granted March 6, 1928, on an application of William C. Stewart. This knife is preceded by a hold-down in the form of a roll 372 also of the character disclosed in said Letters Patent. Movement of the knife 370 transversely across the sole of a shoe presented to the machine, from one edge of the sole to the other at its heel breast line, will form in the sole a flap the rear end of which is thin but the forward portion of which, at or slightly forward of the heel breast line, is thicker, the flap being of the character shown in Letters Patent of the United States No. 1,527,963, granted February 24, 1925, on an application filed in the name of John L. Preo and Isabelle Henne. The forwardly projecting portion of the breast of a Louis heel may be positioned beneath this flap, as also disclosed in said Letters Patent.

If the hand lever 252 is depressed while the parts are in the condition just described, with the pin 250 engaging a downwardly projecting portion 356 of the slot 262, the rotation of the crank disk 254 is effective to move the slide bar 264 in such a manner that the knife 370 carried thereby will move transversely across the sole of the shoe, from one edge to the other, cutting in the sole a flap of the character described. During the first half of the return stroke of the crank disk 254, however, the connecting rod 258

strikes the table 20 and its left-hand end is rocked upwardly, moving the pin 260 up out of the depressed portion of the slot 262 so that the guide bar 264 will return to its extreme right-hand position, as shown in Figs. 1 and 2.

After the heel breast receiving abutment has been formed in either of the ways which have been described, the machine is operated 10 to trim the surplus stock from and to bevel the periphery of the heel-seat portion of the sole of the shoe so that the peripheral portion of the heel-seat will be left in the condition shown in Fig. 13. For this purpose the cutter carrier 74 and the cutter 76 carried thereby are moved peripherally of the heel-seat portion of the sole of a shoe by mechanism which will now be described.

By referring to Figs. 5 and 6, it will be 20 seen that the left-hand forward portion of the left-hand crease plate 64 is cut away to receive a transversely slidable block 400, the right-hand end surface 402 of which, when the block is slid to its right-hand position as 25 shown in Fig. 6, forms a continuation of the left-hand vertical surface of the guide groove 70 of the crease plate 64. A pin 404 extends upwardly from the block 400 and is received in a slot 406 at the forward end of a lever 30 408 fulcrumed at 410 to the table 20 and connected by a pin and slot connection 412 with a lever 414 fulcrumed at 416 to the table 20 and the rear end of which is connected by a transversely extending link 418 35 with a horizontally movable lever 420 (best shown in Figs. 1, 6 and 9) fulcrumed at 422 (Fig. 6) near the rear of the head 18 of the machine and having pivoted to its front end at 424 (Fig. 9) for vertical swinging movement a bell crank lever 426, the forward end of which serves as a handle by which the lever 420 may be moved transversely of the machine.

When the machine is in inoperative position 45 and while the heel breast receiving abutment is being formed, the block 400 is positioned to the left, as shown in Fig. 5. After the heel breast receiving abutment has been formed, however, the lever 426 is moved to 50 the left, causing the block 400 to move to the right to the position shown in Fig. 6, in which movement it is guided by a slideway 430 formed in the table 20 and receiving a rib projecting from the block 400. When 55 once it reaches this position, the block 400 is latched therein by a pivoted latch member 432 (Fig. 5) the left-hand end of which engages a shoulder 434 carried by the table 20, the right-hand end of the latch being held 60 in elevated position by a spring 436. The latch 432 is effective only when the cutter carrier 74 is in a position other than its left-hand forward position at which time the right-hand end of the latch member 432 is held depressed by the cutter carrier 74.

Near its right-hand end the block 400 is provided with an upwardly extending rib 438 received in a groove formed in the lower surface of the cutter carrier 74 so that when the cutter carrier 74 is at the left-hand end 70 of its path of movement, it can be moved transversely of the machine with the block 400.

A latching member 440 (Figs. 1 and 2) is pivoted at 442 to the head 18 of the machine 75 and is held upwardly by a spring 444 at its left-hand end. A lug 446, the right-hand surface of which is inclined relatively to the body of the latch member 440 but the left-hand surface of which is vertical, projects 80 upwardly from the latch member 440 and serves to retain the lever 426 in its left-hand position when it is moved thereto and thus holds the block 400 in its right-hand position, independently of the operation of the latch 432, until the lever 426 is moved to the right to its inoperative position. When the cutter carrier 74 is moved toward the rear, the latch 432 becomes effective and is effective to hold the block 400 in its right-hand position, as 85 shown in Fig. 6, until the cutter carrier 74 has been moved peripherally of the heel-seat 90 portion of the sole of a shoe to trim surplus material therefrom and has been returned again to the position of Fig. 6 at which time it engages an inclined portion 450 formed at the rear of the right-hand end of the latch 432 and forces the right-hand end of the latch downwardly, thus releasing the latch so that the block 400 can be moved to the left to the position 95 shown in Fig. 5. The utilization of the cutter carrier 74 to unlatch the block 400 prevents the movement of the block 400 to the left before the cutter carrier 74 has moved into such a position that it may be moved to 100 the left with the block 400 and thus constitutes an effective safety device and prevents jamming and possible injury to the machine.

The cutting edge of the knife 76, indicated at 464, is inclined and may be slightly curved 110 relatively to the plane top surface of the crease plates 62, 64. The sole of the shoe is engaged immediately in front of the knife 76 by a spring-pressed holddown member 466 (Fig. 5) carried by an arm 460 projecting 115 from the cutter carrier 74 immediately in front of the knife 76. A pin 462 passes through a slot 468 near the front end of a rearwardly extending pitman 470 (Figs. 5 and 6) which is operative to move the cutter 120 carrier 74 peripherally of the heel seat of the shoe. A short slide block 472 positioned in the slot 468 receives the pin 462 and together with the pin is urged rearwardly by a spring 474 connected at one end to the slide block 125 472 and at the other end to the pitman 470. This construction is effective to prevent jamming of the cutter carrier 74 in the guide groove 70 as the cutter carrier is moved about the rear portion of the guide 70 under the 130

various positions of adjustment which the increase plates take when the machine is operating upon shoes of different sizes.

The rear end of the pitman 470 constitutes 5 the eccentric strap 480 of an eccentric 482 (Figs. 6 and 9) fast upon the upper end of a vertical shaft 484 suitably journaled in a transmission gear casing 486 formed at the left right-hand portion of the head 18 of the 10 machine. A stationary pin 488 depending from a cover plate 490 which protects the eccentric, the rear portion of the pitman, and adjacent parts of the machine, projects into a hole 492 in the pitman (Fig. 6). The rear 15 portion of this hole 492 is of such a size that the pin 488 clears its walls at all times. The forward portion 494 of the hole 492 engages the pin 488 as the cutter carrier 74 moves about the rear of the shoe, guided by the rear 20 portion of the guide groove 70, and serves as a fulcrum about which the pitman 470 swings at that time.

The eccentric 482 is driven from the motor 263 by mechanism which will now be described. Fast on the shaft 255 is a spiral gear 500 (Figs. 6 and 9) meshing with a spiral gear 502 of a reversible transmission gearing contained in the gear casing 486 through which passes the shaft 484 of the eccentric 482. Formed integrally with the spiral gear 502 is a bevel gear 506, these gears, which are continuously driven, being loose upon the shaft 484 but restrained against movement lengthwise of the shaft. Meshing with the 35 bevel gear 506 is a bevel gear 508 mounted on a stub shaft 510 carried by the transmission gear casing 486 and meshing also with a bevel gear 512 loose upon the shaft 484. The lower bearing 514 for the shaft 484 extends downwardly from the bottom of the gear casing 486, as shown in Fig. 9, a collar 516 being fast upon the shaft 484 below the bearing 514. Tending to rotate the shaft 484 and the eccentric 482 in a clockwise direction, as viewed 40 in Figs. 6 and 10, is a spring 518 (Fig. 9) secured at one end to the collar 516 and at the other to the bearing 514. Splined to the shaft 484 between the bevel gears 506 and 508 is a sleeve 520 having a dog 522 projecting 45 from each end thereof, the dogs being arranged, when the sleeve is slid one way or the other, to engage cooperating slots 524 formed in the hubs of the bevel gears 506, 512. Thus, by sliding the sleeve 520 in one direction or the other, the eccentric 482 may 50 be driven in either direction. When the sleeve 520 is in its intermediate position, the gearing is in neutral and the shaft 484 and the eccentric 482 remain at rest.

55 Depression of the hand lever 426 is effective to lower the sleeve 520, thereby causing the gear 512 to rotate the shaft 484 and the eccentric 482 in a counterclockwise direction, as viewed in Fig. 6. This moves the cutter carrier 74, which at this time is in the posi-

tion shown in Fig. 6, and the cutter 76 peripherally of the heel-seat of the sole of the shoe to be operated upon, trimming surplus material from and beveling the periphery of the heel-seat, the cutter carrier 74 coming to rest at the right-hand end of the groove 70. The connections between the lever 426 and the sleeve 520 include a link 529 (Fig. 9) pivoted at 530 to the upwardly extending arm of the bell crank lever 426 and at 532 to the upwardly extending arm of another bell crank lever 534 fulcrumed at 536 inside the gear casing 486 and having a rearwardly extending arm 538 provided with a slot near its end in which is located a pin 540 (Fig. 11) arranged at the rear of a lever 542 fulcrumed in the gear casing 486 and having at its forward end a yoke 544 pivoted to a U-shaped member 546 positioned in a groove in the sleeve 520. A compression spring 550, bearing at one end against the lever 542 between its fulcrum and the pin 540 and at the other end against a stationary part, tends to rock the lever 542 in a clockwise direction, as viewed in Fig. 11, and to lift the sleeve 520 to its neutral position. The link 529 is illustrated as made up of two yieldingly connected parts, as shown at 531, so that the downward movement of the hand grip of the lever 426 will be somewhat cushioned and downward movement in excess of that necessary to shift the transmission gearing will be harmless.

Mechanism, which will now be described, is provided to throw the transmission gearing into neutral when the cutter carrier 74 has completed its movement and has arrived at the right-hand end of the guide groove 70. For this purpose the eccentric 482 is provided with a lug 560 on its lower surface, the lug 560 having a pair of inclined surfaces 562, 564 arranged, when the eccentric has completed somewhat less than a single cycle of revolution in either direction and when the cutter carrier 74, accordingly, has reached one end or the other of its path of movement, to throw the transmission mechanism into neutral. As the forward motion of the cutter carrier 74 must be varied in accordance with the length to which the heel-seat of a shoe is to be trimmed, means is provided for varying the point in the cycle of revolution of the eccentric 482 at which the surfaces 562 and 564, respectively, are effective to throw the transmission gearing into neutral. For this purpose a pair of gear sectors 570, 572 (Figs. 6 and 10) are pivoted at 574, 576 to the table 20 beneath the cover plate 490, meshing with each other forwardly of the shaft 484. The gear sector 570 is connected by a link 580 with an arm 582 adjustably secured to and movable with the movable head 24. Thus the position of the gear sectors 570, 572 is dependent upon the position of the movable head 24. As the latter is moved forwardly

to adjust the machine to operate upon a shoe to which a longer heel is to be attached, the rear portion of the gear sectors 570, 572 move toward each other and forwardly. Each of these gear sectors is bored at its rear portion to house a plunger 586 (Figs. 9, 10 and 11) at the upper end of which is a cap 588, having a conical upper end arranged for engagement with one or the other of the surfaces 562, 564 of the lug 560 as the eccentric reaches the end of its revolution. The lower ends of the plungers 586 are positioned adjacent to and over the ends of a two-armed lever 590 fulcrumed at 592 (Figs. 10 and 11) to the gear casing 486 and connected by a link 594 with the lever 542. When the eccentric 482 reaches the end of its revolution in a counter-clockwise direction, as viewed in Fig. 10, the surface 564 will engage the cap 588 at the upper end of the plunger 586 carried by the gear sector 572 so that the plunger will be depressed, rocking the lever 590 a few degrees in a clockwise direction, as viewed in Fig. 11, thus raising the U-shaped member 546 and the sleeve 520 and throwing the transmission gearing into neutral. At this time the heel-seat fitting operation will have been finished. The hand lever 426 will next be raised, as more fully hereinafter described, raising the sleeve 520 and causing the transmission gearing to rotate the eccentric 482 in a clockwise direction, as viewed in Fig. 6, thus returning the cutter carrier 74 to the left-hand end of the guide groove 70. When the cutter carrier 74 reaches this position, the surface 562 of the lug 560 will engage the cap 588 of the plunger 586 carried by the gear sector 570 and the transmission gearing will again be thrown into neutral so that the cutter carrier 74 will come to rest. Adjustment of the movable head 24 forwardly will permit the eccentric 482 more nearly to complete a single cycle of revolution while adjustment of the movable head 24 rearwardly will have the opposite effect. As the movable head 24 is adjusted forwardly, the spring 518 causes the eccentric 482 to revolve, maintaining the guide surface 564 in engagement with the cap 588 of the plunger 586 carried by the gear sector 570. In order to facilitate the operation of the machine, the hand lever 110 is provided with an arm 600 arranged, as the hand lever 110 is moved upwardly to release a shoe at the conclusion of the operation, to strike the lever 426, thereby moving the forward end of the latter upwardly to cause the transmission gearing to effect the return movement of the eccentric 482 and the cutter carrier 74. Thus, it is not necessary for the operator to raise the lever 426 as a separate step in the operation of the machine.

The upward movement of the lever 110, moreover, is utilized to release the treadle dog 230 from the latch plate 234, thereby permitting the lever 160 to be elevated by a

spring 602 with which it is provided so that the lever 166 may move upwardly, permitting the holddown 180 to be elevated at the conclusion of the operation upon a shoe to which a Cuban heel is to be attached without further attention on the part of the operator. For this purpose the lever 110 is connected by a rod 604 (Fig. 4) with a rearwardly extending arm 606 connected to the dog 230, the arrangement being such that elevation of the lever 110 rocks the dog 230 in a clockwise direction, as viewed in Fig. 4. The rod 604 is provided with a connection 608 permitting lost motion so that it does not interfere with the release of the dog 230 by the supplemental treadle 360 when it is desired to operate the machine in that manner.

It will be remembered that the levers 420 and 426 are latched in their left-hand position, as illustrated in Fig. 1, while the trimming operation is being performed. Mechanism, which will now be described, is provided for unlatching this lever and returning it to its right-hand position at the conclusion of the operation. For this purpose the left-hand end of the latch 440 is provided with a pin 612 positioned in a slot 614 formed at the upper end of a rod 616 the lower end of which is connected to a lever 618 (Figs. 1, 4 and 9) fulcrumed at 92 to the bracket 94 and rigidly secured to the cams 96 so that, when the latter are moved forwardly as a result of the raising of the lever 110, the latch 440 will be depressed, thus withdrawing the shoulder 446 from the lever 420 and permitting that lever to be moved to the right by a spring 620 provided for that purpose and correspondingly to move the block 400 to the left to the position shown in Fig. 5.

Gage mechanism, which may be used to position the shoe carried by the work support 80 and the rand crease of which is engaged by the edges 68 of the crease plates 62, 64, is illustrated particularly in Fig. 7. For this purpose a back gage 630 is carried at the forward end of a slide 632 mounted for sliding movement in ways formed in the under side of the table 20 to the rear of the center about which the crease plates 62, 64 are adjustable. A pin 634 extends downwardly from the slide 632 and is engaged by the end of a lever 636 fulcrumed at 638 to the table 20 and the other end of which is pivoted to a block 640 threaded to receive the rear end of a hand screw 642 mounted for rotary movement but restrained against longitudinal movement in a plate 644 secured to the head of the machine, as best shown in Fig. 1. Thus the gage 630 may be adjusted manually by the rotation of the screw 642 which is provided at its forward end with a knurled head to facilitate such adjustment.

The machine may, if desired, also be provided with a pair of side gages 650, 652 (Fig. 7) arranged to engage the upper of the shoe

adjacent to the sole in the neighborhood of the heel breast line, thereby positioning the shoe transversely in the machine. These side gages 650, 652 are arranged for adjustment 5 transversely of the shoe both in the same direction so that the median line of the shoe to be operated upon may be swung slightly out of alignment with the median line of the guide groove 70, if it is desired to extend the trimming cut a little further forward on the right side than on the left side of a right shoe and correspondingly further forward on the left side than on the right side of a left shoe. For this purpose the side gages 10 650, 652 are pivoted to a pair of slide members 654, 656 mounted for transverse movement in ways carried by the crease plates 62, 64. The rear ends of the slide members 654, 656 engage a pair of slidable wedges 658, 660 15 which in turn engage a pair of stationary but adjustable wedges 662, 664 carried by the crease plates. The wedge 658 is connected by a link 666 to a lever 668 fulcrumed at 670 to the crease plate 62 and provided at its 20 other end with a slot 672 in which is positioned a pin 674 mounted in a corresponding lever 676 fulcrumed at 678 to the crease plate 64 and connected at its other end to a link 680 pivoted to the rear end of the wedge 660. 25 The forward end of the wedge 660 is connected by a link 682 to a manually operable bell crank lever 684 fulcrumed at 686 to the head of the machine. The bell crank lever 684, when rotated in a clockwise direction, 30 as viewed in Fig. 7, will move the wedges 660, 658 forwardly, thus moving the side gages 650, 652 to the left while, if the bell crank lever 684 is rotated in the opposite direction, the side gages will be moved to the right. 35 If it is not desired to use this mechanism, the lever 684 may be placed in an intermediate position.

While the operation has repeatedly been referred to in connection with the description 40 of its construction, it will now be described briefly in connection with the performance of the heel-seat fitting operation upon a shoe to which a Cuban heel is to be attached. The shoe to be operated upon is placed on the last pin 82 (Fig. 2), the work support 80 at that time leaning forwardly from its pivot 92. The shoe is then moved rearwardly, carrying the work support with it, the hand lever 110 at the same time being depressed so that the edges 68 of the crease 45 plates 62, 64 enter the rand crease of the shoe. As this takes place the cams 96, moving in a clockwise direction as viewed in Fig. 4, force the shoe upwardly against the lower surface of the edge portion of the crease plates 62, 64, the shoe thus being securely held and the position of the crease plates and of the guide groove 70 being determined by the width of the shoe. The position of the 50 shoe longitudinally in the machine is deter-

mined by the back gage 630, and the side gages 650, 652 may be utilized to determine its transverse position if desired.

With the shoe thus positioned, the operator steps upon the treadle 160, thus rocking the lever 166 downwardly and moving the holdown member 180 into engagement with the heel-seat portion of the sole of a shoe, at the same time causing the rod 170, which at that time projects above the roll 174 carried 70 by the pin 176, to move the slide 144 downwardly and bringing the holdown members 190 into engagement with the sole of the shoe forwardly of its heel breast line. The slide 144 is held in this position by engagement 75 of the dog 230 beneath the latch plate 234. With the parts in this position the operator depresses the lever 252, causing the clutch 250 to become operative and thus causing the crank disk 254 and the connecting rod 258 to 80 move the slide bar 264 transversely of the machine and causing its plate 266 to engage the right-hand end of the rack bar 236, thus rotating the vertical rock shaft 200 and causing the cutter 204 to move transversely across 85 the shoe at its heel breast line, forming a heel breast receiving abutment in the sole of the shoe. As the cutter 204 passes the median portion of the sole of the shoe, the shaft 200 and the cutter 204 are moved height- 90 wise of the shoe so that the abutment formed in the shoe is made of two separate parts of the form shown in Fig. 12. The slide bar 264 is returned to the position shown in Fig. 2 by the spring 280 and the rack bar 236 100 and the cutter 204 are returned by the lever 238 and its spring 242. During the return of the guide bar 264, the shoulder 308 of the guide bar catches the lower end of the lever 302, rocking that lever somewhat in a counter-clockwise direction, and by reason of the link 300 rocking the lever 302 in a clockwise direction so that the rod 170 is moved to the right, releasing the slide 144 which is moved upwardly by the spring 152. The rod 170 is 110 latched in position at that time by the latch 296 which engages the shoulder 298 of the rod 170. The operator now grasps the lever 426, moving it to the left to the position shown 115 in Fig. 1, in which position it is latched by the latch member 440. This moves the slide block 400 to the right from the left-hand position which it has occupied up to this time, bringing its surface 402 into alignment 120 with the left-hand vertical surface of the left-hand end of the guide groove 70 so that the cutter carrier 74 may be moved peripherally of the heel-seat of the shoe under the control of the guide groove 70. This movement of the block 400 brings the cutter 76 and the holdown 466 into engagement with the shoe in the manner indicated in Fig. 12. Depression of the lever 426 is in turn effective 125 to cause the transmission mechanism to rotate 130

the eccentric 482 through nearly a complete revolution, causing the cutter 76 to travel peripherally of the heel-seat and finally to come to rest, after completing the trimming operation, adjacent to the heel breast line at the other side of the shoe. The operator then grasps the hand lever 110 and the lever 116 which controls the pawl 116, releasing the pawl and raising the lever 110, at the same time manually moving the shoe and the work support forwardly.

The upward movement of the lever 110 causes its arm 600 to strike the lever 426, raising that lever and thus rendering the transmission mechanism effective to rotate the eccentric 482 in the reverse direction, returning the cutter carrier 74 rearwardly of the shoe and then to the left-hand end of the groove 70. As the cutter carrier reaches this position it engages the inclined surface 450 of the latch 432, releasing the latch which up to that time had retained the block 400 in its right-hand position. This permits the block 400 to move to the left, carrying with it the cutter carrier 74. Shortly before this the latch 440 has been released by the forward movement of the work support 80 so that when the latch 432 is released the block 400 and the lever 426 are free to be moved to the left and to the right, respectively. The upward movement of the lever 110, moreover, is effective to release the dog 230 from the plate 234 so that the treadle 160 may be raised by its spring 602 and the lever 166 is thereby moved upwardly, the latch 296 at this time being moved rearwardly by its spring 303 to release the rod 170.

Having thus described my invention, what I claim as new and desire to secure by Letters Patent of the United States is:

1. A heel-seat fitting machine having, in combination, crease plates formed and arranged to enter the rand crease of a shoe and each provided with a plane surface to contact with the attaching surface of the sole of the shoe, a knife carrier movable about the periphery of the heel-seat portion of the sole of a shoe the attaching surface of the sole of which is in engagement with said surfaces, and a drag knife carried by the carrier and having a cutting edge inclined relatively to said surfaces of the crease plates to trim surplus material from and to bevel the heel-seat portion of the sole of the shoe.

2. A heel-seat fitting machine having, in combination, a support for a shoe, crease plates formed and arranged to enter the rand crease of a shoe carried by the support, said crease plates being provided with guides substantially parallel to their rand crease entering edges, and a cutter constructed and arranged for movement peripherally of the heel-seat of the sole of a shoe carried by the support to trim surplus material therefrom and to bevel the periphery of the heel-seat

portion of the sole, said cutter being guided in its peripheral movement by said guides.

3. A heel-seat fitting machine having, in combination, a support for a shoe, crease plates formed and arranged to enter the rand crease of a shoe carried by the support and each provided with a guide substantially parallel to its rand crease entering edge, a cutter carrier movable about the periphery of the heel-seat portion of the sole of the shoe under the control of said guides, and a cutter carried by the carrier and constructed and arranged to trim surplus material from and to bevel the heel-seat portion of the sole.

4. A heel-seat fitting machine having, in combination, crease plates formed and arranged to enter the rand crease of a shoe to be operated upon, said crease plates being provided with guides substantially parallel to their rand crease entering edges, a carrier movable about the periphery of the heel-seat portion of the sole of a shoe the rand crease of which is engaged by said crease plates and guided in its movement by said guides, and a cutter carried by the carrier and constructed and arranged as the carrier moves peripherally of the sole of the shoe to trim surplus material from the periphery of the heel-seat portion of the sole.

5. A heel-seat fitting machine having, in combination, a pair of crease plates formed and arranged to enter the rand crease of a shoe to be operated upon and adjustable about a point substantially in line with the back seam of the shoe, said crease plates each being provided with a guide substantially parallel to its rand crease entering edge, a carrier movable about the periphery of the heel-seat portion of the sole of a shoe the rand crease of which is engaged by said crease plates, and guided in its movement by said guides, and a drag knife carried by the carrier and arranged as the carrier moves peripherally of the sole of the shoe to trim surplus material from and to bevel the heel-seat portion of the sole.

6. A heel-seat fitting machine having, in combination, a support for a shoe, crease plates arranged to enter the rand crease of a shoe carried by the support and mounted for adjustment toward and from the rand crease of the shoe, each crease plate being provided with a guide groove parallel to its rand crease entering edge, a cutter carrier having a projection positioned in said guide groove, a cutter carried by the carrier, and means for moving the carrier and the cutter peripherally of the heel-seat portion of a shoe carried by the support and the rand crease of which is engaged by the crease plates to trim surplus material from the heel-seat portion of the sole of the shoe.

7. A heel-seat fitting machine having, in combination, a support for a shoe, a pair

of crease plates formed and arranged to enter the rand crease of a shoe carried by the support and mounted for arcuate adjustment about a point substantially in line with the back seam of a shoe carried by the support, said crease plates each being provided with a guide parallel to its rand crease entering edge, a cutter carrier guided by said guides peripherally of the heel-seat portion of the sole of the shoe, and a cutter carried by the carrier and operated by the peripheral movement thereof to trim surplus material from and to bevel the heel-seat portion of the sole of the shoe.

15 8. A heel-seat fitting machine having, in combination, a support for a shoe, a pair of crease plates formed and arranged to enter the rand crease of a shoe carried by the support and adjustable about a point substantially in line with the back seam of a shoe carried by the support, said crease plates being provided with guides substantially parallel to their rand crease entering edges, and a drag knife arranged for movement peripherally of the heel-seat of the sole of a shoe carried by the support to trim surplus material therefrom and to bevel the periphery of the heel-seat portion of the sole, said knife being guided in its peripheral movement by said guides.

9. A heel-seat fitting machine having, in combination, a support for a shoe, a pair of crease plates arranged to enter the rand crease of a shoe carried by the support and mounted for arcuate adjustment about a point substantially in alinement with the back seam of the shoe, each crease plate being provided with a guide groove parallel to its rand crease entering edge, a cutter carrier having a pair of rolls positioned in said guide groove, a cutter carried by the carrier, and means for moving the carrier and the cutter peripherally of the heel-seat portion of a shoe carried by the support, and the rand crease of which is engaged by the crease plates, to trim surplus material from and to bevel the heel-seat portion of the sole of the shoe.

10. A heel-seat fitting machine having, in combination, a support for a shoe, a cutter carrier arranged for movement peripherally of the heel-seat portion of the sole of a shoe carried by the support, a cutter carried by the carrier and arranged for movement therewith to trim surplus material from and to bevel the peripheral portion of the heel-seat of the sole of a shoe carried by the support, means constructed and arranged to guide the cutter carrier in a path extending transversely of the sole and to prevent movement of the cutter carrier out of said path, and means for moving the cutter carrier along said path to bring the cutter into engagement with the peripheral portion of the sole substantially at its heel-breast line at

the start of the operation and for moving the cutter and cutter carrier transversely away from the sole after the operation has been concluded.

11. A heel-seat fitting machine having, in combination, a support for a shoe, a cutter arranged for movement peripherally of the heel-seat portion of the sole of a shoe carried by the support to trim surplus material from and to bevel the peripheral portion of the heel-seat of the sole, means constructed and arranged to guide the cutter in a path extending transversely of the sole and to prevent movement of the cutter out of said path, and means for moving the cutter along said path to bring the cutter into engagement with the peripheral portion of the sole substantially at its heel-breast line at the start of the operation and for moving the cutter transversely away from the sole after the operation has been concluded.

12. A heel-seat fitting machine having, in combination, a support for a shoe, a pair of crease plates arranged to engage the rand crease of a shoe carried by the support and mounted for adjustment about a point substantially in alinement with the back seam of the shoe carried by the support, a guide carried by the crease plates and extending substantially parallel to their edges, a cutter carrier mounted for movement peripherally of the sole of a shoe carried by the support and guided in its movement by said guide, a cutter carried by the carrier and arranged for movement therewith to trim surplus material from and to bevel the heel-seat portion of the sole, and means for moving the cutter carrier transversely of the sole of a shoe carried by the support to bring the carrier into alinement with the guide and to bring the cutter into engagement with the peripheral portion of the sole of the shoe at its heel-breast line at the start of the operation and for moving the cutter carrier away from the guide and the cutter away from the sole after the operation has been completed.

13. A heel-seat fitting machine having, in combination, a support for a shoe, a pair of crease plates formed and arranged to enter the rand crease of the sole of a shoe carried by the support and mounted for arcuate adjustment about a point substantially in line with the back seam of a shoe carried by the support, said crease plates each being provided with a guide groove parallel to its rand crease entering edge, a block mounted for movement toward and from the edge of the forward portion of one of the crease plates into and out of operative position and provided with a surface which forms a continuation of one of the surfaces of the guide grooves when the block is moved toward the edge of said crease plates to its operative position, a carrier arranged for movement with said guide block toward and from the edge

of said crease plate and also for movement, when the guide block has been moved toward said crease plate to its operative position, peripherally of the crease plates under the control of said guide groove, means for moving said block toward and from the edge of said crease plate, and means for moving the carrier peripherally of the crease plates under the control of said guide groove to cause the cutter to trim surplus material from the heel-seat portion of the sole of a shoe.

14. A heel-seat fitting machine having, in combination, a support for a shoe, a cutter, a member extending peripherally of the sole of the shoe carried by the support and constructed and arranged to guide the cutter in a path and to prevent movement of the cutter out of said path, an eccentric, and connections between the eccentric and the cutter arranged, as the eccentric is revolved, to move the cutter under the control of its guide member peripherally of the heel-seat of the sole of a shoe carried by the support to trim surplus material therefrom.

15. A heel-seat fitting machine having, in combination, a support for a shoe, a cutter, a member extending peripherally of the sole of the shoe carried by the support and constructed and arranged to guide the cutter in a path and to prevent movement of the cutter out of said path, an eccentric, an eccentric strap cooperating with the eccentric and having a pitman pivotally connected thereto, and means for revolving the eccentric, thereby to move the cutter under the control of its guide member peripherally of the heel-seat of the sole of a shoe carried by the support to trim surplus material therefrom.

16. A heel-seat fitting machine having, in combination, a cutter, means for guiding the cutter peripherally of the heel-seat portion of the sole of a shoe, an eccentric, means for causing the eccentric to operate through a part of a revolution and then to come to rest, and an eccentric strap surrounding the eccentric and connected to the cutter, said strap being arranged to cause the cutter to operate about the periphery of the heel-seat portion of the sole, from one end of the heel-breast line to the other end of the heel-breast line, as the eccentric revolves, and then to come to rest.

17. A heel-seat fitting machine having, in combination, a support for a shoe, a pair of crease plates formed and arranged to enter the rand crease of a shoe carried by the support and mounted for arcuate adjustment about a point substantially in line with the back seam of a shoe carried by the support, said crease plates each being provided with a groove parallel to its rand crease entering edge, a knife carrier guided by said grooves, an eccentric, connections from the eccentric to the knife carrier effective upon rotation of the eccentric to move the carrier periph-

erally of the heel-seat portion of the sole of the shoe, and a cutter carried by the carrier and arranged by the peripheral movement thereof to trim surplus material from and to bevel the heel-seat portion of the sole of the shoe.

18. A heel-seat fitting machine having, in combination, a support for a shoe, a cutter guided for movement peripherally of the heel-seat portion of the sole of a shoe carried by the support, an eccentric, an eccentric strap cooperating with the eccentric and having a pitman connected to the cutter to move the cutter under the control of its guide peripherally of the heel-seat of the sole of a shoe to trim surplus material therefrom and formed with a hole between its ends, and a stationary pin positioned in said hole in the pitman and serving as a fulcrum about which the pitman rocks as the cutter is moved about the extreme rear end of the sole.

19. A heel-seat fitting machine having, in combination, a cutter, means for guiding the cutter peripherally of the heel-seat portion of the sole of a shoe, an eccentric, means for causing the eccentric to operate through nearly one revolution and then to come to rest, an eccentric strap surrounding the eccentric and connected to the cutter, said strap being arranged to cause the cutter to operate about the periphery of the heel-seat portion of the sole, from one end of the heel-breast line around the rear of the heel-seat and then forwardly to the other end of the heel-breast line, as the eccentric revolves, and means for causing the eccentric to make nearly one revolution in the opposite direction to return the cutter to its original position.

20. A heel-seat fitting machine having, in combination, a support for a shoe, a cutter arranged for movement peripherally of the heel-seat portion of the sole of a shoe carried by the support to trim surplus material therefrom, gearing arranged to move the cutter peripherally of the heel-seat portion of the sole of the shoe, a manually operable controller arranged to cause the gearing to stop or move the cutter at any position peripherally of the heel-seat of the sole of the shoe to trim surplus material therefrom, and means automatically to throw the gearing out of operation at the conclusion of the trimming operation.

21. A heel-seat fitting machine having, in combination, a cutter arranged to operate peripherally of the heel-seat portion of the sole of a shoe, an eccentric, an eccentric strap cooperating with the eccentric and having a pitman connected to the cutter, transmission mechanism arranged to drive the eccentric, a manually operable controller arranged to cause the transmission mechanism to revolve the eccentric and thereby to move the cutter peripherally of the heel-seat of the sole to trim surplus material therefrom, and

means carried by the eccentric arranged automatically to throw the transmission mechanism out of operation at the conclusion of the trimming operation.

22. A heel-seat fitting machine having, in combination, a cutter arranged for movement peripherally of the heel-seat of the sole of a shoe, from one end of the heel-breast line around the rear of the heel-seat and then forwardly to the other end of the heel-breast line, to trim surplus material from and to bevel the heel-seat, an eccentric, connections from the eccentric to the cutter arranged to cause rotation of the eccentric to move the cutter peripherally of the heel-seat, transmission mechanism arranged to revolve the eccentric in either direction and having also a neutral position, means for automatically shifting the transmission mechanism into the neutral position somewhat before the end of a complete cycle of revolution of the eccentric, and adjustable means for determining the point in the cycle of revolution of the eccentric at which it is started and stopped whereby the length to which the heel-seat is trimmed may be varied.

23. A heel-seat fitting machine having, in combination, a support for a shoe, a cutter having a single cutting edge, and means for moving the cutter transversely across the sole of a shoe carried by the support from one edge of the sole to the other substantially at its heel-breast line in a curved path the end portions of which correspond to the transverse curvature of corresponding portions of a heel-breast to cause the cutter to form a heel-breast receiving abutment in the sole of the shoe.

24. A heel-seat fitting machine having, in combination, a support for a shoe, a cutter, and means for causing relative progressive movement of the cutter and the support in a direction extending transversely of the sole of a shoe carried by the support from one edge of the sole to the other in a path the end portions of which are inclined relatively to the median line of the shoe to correspond to the transverse curvature of corresponding portions of a heel-breast whereby the cutter operates first at one end and later at the other end of the heel breast line of the sole to form a heel-breast receiving abutment in the sole.

25. A heel-seat fitting machine having, in combination, means for positioning a shoe, a cutter having a single cutting edge mounted for movement transversely across the sole of the shoe from one edge of the sole to the other substantially at its heel-breast line in a path the portions of which adjacent to the edges of the sole are inclined transversely of the shoe whereby the cutter will form a heel-breast receiving abutment in the sole of the shoe shaped to receive a transversely curved heel-breast.

26. A heel-seat fitting machine having, in combination, a support for a shoe, a cutter for forming a heel-breast receiving abutment substantially at the heel-breast line of the sole of a shoe carried by the support, and means for causing relative progressive movement of the cutter and the shoe in a path extending transversely across the sole of the shoe, from one edge of the sole to the other, and inclined relatively to the median line of the shoe to cause the cutter to operate first at one end and later at the other end of the heel breast line of the sole of the shoe to form an abutment shaped and positioned to receive the breast of a Cuban heel.

27. A heel-seat fitting machine having, in combination, a support for a shoe, a cutter to form a heel-breast receiving abutment in the sole of the shoe, and power-operated means for causing relative progressive movement of the support and the cutter in a path extending in a curve transversely across the sole of the shoe, from one edge of the sole to the other, to cause the cutter to operate first at one end and later at the other end of the heel breast line of the sole of the shoe to form a heel-breast receiving abutment conforming to the shape of the transversely carried breast of a Cuban heel.

28. A heel-seat fitting machine having, in combination, means for positioning a shoe, a cutter mounted for progressive movement transversely across the sole of a shoe positioned by said means, from one edge of the sole to the other, substantially at its heel-breast line in a path portions of which adjacent to the edges of the sole are inclined transversely of the shoe, whereby the cutter will operate first at one end and later at the other end of the heel breast line of the sole to form a heel-breast receiving abutment in the sole shaped to receive a transversely curved heel-breast, and power-operated means for moving the cutter in said path across the sole of the shoe from one edge of the sole to the other.

29. A heel-seat fitting machine having, in combination, a support for a shoe, a cutter having a single cutting edge, and power-operated means for moving the cutter transversely across the sole of the shoe from one edge of the sole to the other substantially at its heel-breast line in a curved path to form a heel-breast receiving abutment in the sole.

30. A heel-seat fitting machine having, in combination, a support arranged to hold a shoe in stationary position, and a cutter arranged to form a heel-breast receiving abutment in the sole of a shoe carried by the support, said cutter being mounted for progressive movement transversely across the sole of the shoe from one edge of the sole to the other substantially at its heel-breast line in a curved path corresponding to the transverse curvature of a heel-breast whereby the cutter

operates first at one end and later at the other end of the heel breast line of the sole to form a heel breast receiving abutment in the sole.

31. A heel-seat fitting machine having, in combination, a support for a shoe, a cutter, means for progressively moving the cutter in a curved path transversely across the sole of the shoe mounted upon the support from one edge of the sole to the other whereby the cutter operates first at one end and later at the other end of the heel-breast line of the sole, and separate means constructed and arranged to move the cutter heightwise of the shoe as it moves transversely across the sole to vary the depth to which the cutter operates on the sole of the shoe during its movement transversely across the sole.

32. A heel-seat fitting machine having, in combination, a support for a shoe, a cutter, means for progressively moving the cutter in a curved path transversely across the sole of the shoe mounted upon the support from one edge of the sole to the other to form a heel-breast-receiving abutment in the sole, and means for moving the cutter heightwise of the shoe during the transverse movement to cause the cutter to run out of the sole before the median line of the sole is reached and then after the median line of the sole has been passed to enter the sole, whereby the heel-breast-receiving abutment formed in the sole by the cutter will consist of two separate portions which terminate at opposite edges of the sole of the shoe.

33. A heel-seat fitting machine having, in combination, a support for a shoe, a knife, and means for progressively moving the knife in a curved path transversely across the sole of the shoe mounted upon the support from one edge of the sole to the other whereby the knife operates first at one end and later at the other end of the heel-breast line of the sole, and separate means constructed and arranged to move the knife heightwise of the shoe as it moves transversely across the sole as it operates upon the sole to control the depth to which the knife cuts as it passes across the sole.

34. A heel-seat fitting machine having, in combination, a support for a shoe, a cutter mounted for progressive movement transversely across the sole of the shoe from one edge of the sole to the other substantially at its heel-breast line whereby the cutter operates first at one end and later at the other end of the heel breast line of the sole to form a heel-breast receiving abutment in the sole, and a cam for moving the cutter heightwise of the shoe as it operates on the sole of the shoe.

35. A heel-seat fitting machine having, in combination, a support for a shoe, a cutter mounted for progressive movement transversely across the sole of a shoe carried by the support from one edge of the sole to the

other substantially at its heel-breast line whereby the cutter operates first at one end and later at the other end of the heel breast line of the sole to form a heel-breast receiving abutment in the sole, and a cam arranged to move the cutter heightwise of the shoe during said transverse movement to cause the cutter to run out of the sole before the median line of the sole is reached and then, after the median line of the sole has been passed, to enter the sole whereby the heel-breast receiving abutment formed in the sole by the cutter will consist of two separate portions which terminate at opposite edges of the sole of the shoe.

36. A heel-seat fitting machine having, in combination, a support for a shoe, a cutter movable transversely across the sole of a shoe carried by the support to form a heel-breast receiving abutment in the sole of the shoe, and a cam for controlling the position of the cutter heightwise of the shoe arranged to cause the cutter to enter the sole at one edge and cut through the entire thickness of the sole, then, as the cutter is advanced across the sole, to move heightwise of the sole, running out of the sole before the median line of the sole is reached, then, after the median line of the sole has been passed, to move heightwise of the sole in the opposite direction, causing the cutter to enter the sole, and finally to cut through the entire thickness of the sole shortly before it runs out at the edge of the sole opposite to that at which it entered.

37. A heel-seat fitting machine having, in combination, a support for a shoe, a rock-shaft arranged approximately at right angles to the tread surface of the sole of a shoe carried by the support and forwardly of the heel-breast line of the sole, a cutter connected to the shaft and arranged, as the shaft is rocked, to move transversely across the sole substantially at its heel-breast line from one edge of the sole to the other to form a heel-breast receiving abutment in the sole, and means for rocking the shaft.

38. A heel-seat fitting machine having, in combination, a support for a shoe, a rock-shaft arranged approximately at right angles to the tread surface of the sole of a shoe carried by the support and forwardly of the heel-breast line of the sole, a cutter connected to the shaft and arranged, as the shaft is rocked, to move transversely across the sole at its heel-breast line from one edge of the sole to the other to form a heel-breast receiving abutment in the sole, a pinion carried by the shaft, a rack bar engaging the pinion and mounted for endwise movement to rotate the pinion and thereby to rock the shaft, and means for causing endwise movement of the rack bar.

39. A heel-seat fitting machine having, in combination, a support for a shoe, a rock-

shaft extending heightwise of a shoe carried by the support and forwardly of the heel-breast line of the sole of the shoe, a cutter carried by said shaft substantially in alinement with the heel-breast line of the sole of the shoe, means for moving the shaft heightwise of the shoe to move the cutter into and out of transverse alinement with the sole of the shoe, and means for rocking the shaft to move the cutter transversely across the sole of the shoe from one edge of the sole to the other to form a heel-breast receiving abutment in the sole.

40. A heel-seat fitting machine having, in combination, a support for a shoe, a rock-shaft extending heightwise of a shoe carried by the support and forwardly of the heel-breast line of the sole of the shoe, an arm carried by said shaft, a cutter secured to said arm substantially in alinement with the heel-breast line of the sole of the shoe, means for moving the shaft heightwise of the shoe to move the cutter into and out of transverse alinement with the sole of the shoe, and power-operated means for rocking the shaft to move the cutter transversely across the sole of the shoe from one edge of the sole to the other to form a heel-breast receiving abutment in the sole.

41. A heel-seat fitting machine having, in combination, means for positioning a shoe to be operated upon, a rock-shaft extending heightwise of the shoe and forwardly of its heel-breast line, a cutter connected to the shaft and arranged to be moved, by rocking of the shaft transversely across the sole of the shoe from one edge of the sole to the other substantially at its heel-breast line to form a heel-breast receiving abutment in the sole, and a stationary cam engaging a member carried by the shaft to move the shaft heightwise of the shoe during the rocking of the shaft to control the depth to which the knife cuts as it passes across the sole.

42. A heel-seat fitting machine having, in combination, means for positioning a shoe to be operated upon, a shaft extending heightwise of the shoe and forwardly of its heel-breast line, a cutter connected to the shaft and arranged to be moved by rocking of the shaft transversely across the sole of the shoe from one edge of the sole to the other substantially at its heel-breast line to form a heel-breast receiving abutment in the sole, a stationary cam engaging a member carried by the shaft to move the shaft heightwise of the shoe during said transverse movement to control the depth to which the knife cuts as it passes across the sole, and a spring acting on the shaft in opposition to the cam and urging said cam-engaging member into engagement with the cam.

43. A heel-seat fitting machine having, in combination, a support for a shoe, a cutter carrier arranged for movement transversely across the sole of a shoe carried by the sup-

port, a cutter having a single cutting edge carried by the carrier and arranged for movement therewith across the sole of the shoe substantially at its heel-breast line to form a heel-breast receiving abutment in the sole, and a single revolution clutch arranged to transmit power to move the cutter carrier and the cutter transversely of the sole of the shoe to form a heel-breast receiving abutment therein and thereafter to return the cutter carrier and cutter to their normal inoperative positions.

44. A heel-seat fitting machine having, in combination, a support for a shoe, a cutter carrier arranged for movement transversely across the sole of a shoe carried by the support, a cutter carried by the carrier and arranged for movement therewith across the sole of the shoe substantially at its heel-breast line to form a heel-breast receiving abutment in the sole, a single revolution clutch arranged to move the cutter carrier and the cutter transversely of the sole of the shoe to form a heel-breast receiving abutment therein, and a spring energized by said transverse movement of the cutter carrier and arranged to return the cutter carrier and cutter to normal inoperative positions.

45. A heel-seat fitting machine having, in combination, a support for a shoe, two cutters arranged alternatively to operate on the sole of a shoe carried by the support, and a carrier for one of the cutters movement of which operates to move the other cutter relatively to the shoe to operate thereon.

46. A heel-seat fitting machine having, in combination, a support for a shoe, two cutters alternatively operable to form, respectively, portions of a heel-breast receiving abutment in the sole of a shoe carried by the support, and a carrier for one of the cutters, movement of which, through a path which does not bring its cutter into operative relation to a shoe on the support, operates to move the other cutter transversely of the sole of the shoe on the support to form a portion of the heel-breast receiving abutment therein.

47. A heel-seat fitting machine having, in combination, a support for a shoe, a knife constructed and arranged for movement transversely of the sole of a shoe carried by the support at its heel-breast line and formed to make a cut extending transversely of the sole and inclined heightwise of the sole thereby forming substantially at the heel-breast line a flap having a relatively thick base at the forward end of the flap and tapering to a thin end at the rear of the flap beneath which flap the forwardly projecting portion of the breast of a Louis heel may be positioned, a cutter mounted for movement transversely of the sole of the shoe substantially at its heel-breast line in a path the end portions of which are inclined relatively to the median line of

the shoe, said cutter being shaped to form in the sole an approximately vertical heel-breast receiving abutment adapted to receive a Cuban heel, a clutch, and means for operatively connecting the clutch alternatively with said knife or said cutter so that the machine may be operated to form a heel-breast receiving abutment for a Louis heel or a heel-breast receiving abutment for a Cuban heel as may be desired.

48. A heel-seat fitting machine having, in combination, a support for a shoe, a cutter arranged for movement transversely of the sole of a shoe carried by the support from one edge of the sole to the other at its heel-breast line to form an approximately vertical heel-breast receiving abutment in the sole of the shoe adapted to receive a Cuban heel, a rack bar arranged for endwise movement and connected to said cutter to move said cutter transversely of the sole of the shoe, a knife mounted for movement transversely of the sole of a shoe carried by the support substantially at its heel-breast line to form in the sole a flap adapted to constitute an abutment for a Louis heel, a bar, to which said knife is secured, arranged for movement in a direction extending transversely of the sole of the shoe, means for moving said rack bar into the path of movement of the knife-carrying bar whereby movement of the latter, insufficient to cause the knife to operate upon the sole of a shoe carried by the support, will operate the cutter to form a heel-breast receiving abutment in the sole of the shoe to receive a Cuban heel, and means operable for moving the knife-carrying bar in a path to cause its knife to form a heel-breast receiving flap in the sole for the reception of a Louis heel when the cutter is out of operative relation to the sole and for causing the knife-carrying bar to move the rack bar, thereby causing the cutter, when in operative position, to form an abutment in the sole for the reception of a Cuban heel.

49. A heel-seat fitting machine having, in combination, means for trimming surplus material from the peripheral portion of the heel-seat of the sole of a shoe, and a cutter arranged for movement transversely across the sole of the shoe from one edge of the sole to the other substantially at its heel-breast line in a path the portions of which adjacent to the edges of the sole are inclined transversely of the sole to conform to the transverse curvature of the breast of a heel to form a heel-breast receiving abutment in the sole.

50. A heel-seat fitting machine having, in combination, a support for a shoe, a cutter for trimming surplus material from the peripheral portion of the heel-seat of the sole of a shoe carried by the support, and a cutter arranged for movement transversely across the sole of the shoe from one edge of the

sole to the other substantially at its heel-breast line in a path the portions of which adjacent to the edges of the sole are inclined transversely of the sole to conform to the transverse curvature of the breast of a heel to form a heel-breast receiving abutment in the sole.

51. A heel-seat fitting machine having, in combination, a support for a shoe, means for trimming surplus material from the peripheral portion of the heel-seat of the sole of a shoe carried by the support, and a cutter arranged for movement transversely across the sole of the shoe from one edge of the sole to the other substantially at its heel-breast line in a curved path corresponding to the transverse curvature of the breast of a heel to form a heel-breast receiving abutment in the sole.

52. A heel-seat fitting machine having, in combination, a work support arranged to hold a shoe in stationary position, a cutter arranged to form a heel-breast receiving abutment in the sole of a shoe, said cutter being mounted for movement transversely across the sole of the shoe from one edge of the sole to the other substantially at its heel-breast line in a curved path corresponding to the transverse curvature of a heel-breast, and a cutter arranged to trim surplus material from the periphery of the heel-seat portion of the sole.

53. A heel-seat fitting machine having, in combination, a work support, a cutter movable transversely across the sole of a shoe from one edge of the sole to the other substantially at its heel-breast line to form a heel-breast receiving abutment in the sole, a second cutter, means for moving the second cutter transversely of the sole to bring its cutting edge into engagement with the sole where the sole has been cut by the first cutter substantially at one end of its heel-breast line, and power-operated means for moving the second cutter peripherally of the heel-seat portion of the sole to trim surplus material from and to bevel the heel-seat of the sole.

54. A heel-seat fitting machine having, in combination, a work support, a cutter movable transversely across the sole of a shoe carried by the work support from one edge of the sole to the other substantially at its heel breast line in a path the end portions of which are inclined relatively to the median line of the shoe to form a heel breast receiving abutment in the sole corresponding in shape to the transverse curvature of a heel breast, a second cutter, means for moving the second cutter transversely of the sole to bring its cutting edge into engagement with the sole where the sole has been cut by the first cutter substantially at one end of its heel breast line, and means for moving the second cutter peripherally of the heel-seat portion of the sole to trim surplus material

from and to bevel the heel-seat of the sole. 55. A heel-seat fitting machine having, in combination, a support for a shoe, a cutter movable transversely across the sole of a shoe carried by the support to form a heel breast receiving abutment in the sole, a cutter arranged for movement peripherally of the heel-seat portion of the sole of the shoe to trim surplus material therefrom, means for moving said last-named cutter transversely of the sole of the shoe into the cut made by the first cutter, and means for moving the last-mentioned cutter peripherally of the heel-seat portion of the sole to trim surplus material from the sole. 10 15

56. A heel-seat fitting machine having, in combination, a support for a shoe, a cutter arranged for movement transversely across the sole of a shoe carried by the support substantially at its heel breast line and formed and arranged to cut a groove in the sole the forward surface of which serves as a heel breast receiving abutment, a second cutter, means for moving said second cutter transversely of the sole of the shoe into the groove made by the first cutter, and means for thereafter moving the second cutter peripherally of the heel-seat portion of the sole to trim surplus material from and to bevel the heel-seat portion of the sole. 20 25 30

57. A heel-seat fitting machine having, in combination, a support for a shoe, a cutter, means for moving said cutter transversely across the sole of a shoe carried by the support substantially at the heel breast line of the sole from one edge of the sole to the other to groove the sole, the forward surface of said groove serving as a heel breast receiving abutment, means for moving the cutter heightwise of the shoe as it moves transversely across the sole so that the groove and the heel breast receiving abutment are formed of two parts separated by the uncut median portion of the sole, a second cutter, means for moving the second cutter transversely of the sole of the shoe into the groove at one end of the heel breast line, and means for thereafter moving the second cutter peripherally of the heel-seat portion of the sole to trim surplus material therefrom and to bevel the sole. 35 40 45 50

58. A heel-seat fitting machine having, in combination, a support for a shoe, a cutter mounted for movement transversely across the sole of a shoe carried by the support, from one edge of the sole to the other substantially at its heel breast line, to form a heel breast receiving abutment in the sole, a hold-down member, and means for moving said 55 60

60. A heel-seat fitting machine having, in combination, a support for a shoe, a hold-down member heightwise of a shoe carried by the support into engagement with the sole of the shoe. 65

portion of the heel-seat of the sole of a shoe carried by the support, and a cutter mounted for movement transversely across the sole of the shoe from one edge to the other substantially at its heel breast line to form a heel breast receiving abutment in the sole. 70

60. A heel-seat fitting machine having, in combination, a support for a shoe, holddown members arranged to engage the sole of a shoe carried by the support adjacent to the ends of the heel breast line of the sole, and a cutter mounted for movement transversely across the sole from one edge of the sole to the other substantially at its heel breast line to form a heel breast receiving abutment in the sole. 75 80

61. A heel-seat fitting machine having, in combination, a support for a shoe, holddown members arranged to engage the sole of a shoe carried by the support at the central portion of its heel-seat and adjacent to the ends of its heel breast line, and a cutter mounted for movement transversely across the sole of the shoe from one edge of the sole to the other substantially at its heel breast line to form a heel breast receiving abutment in the sole. 85 90

62. A heel-seat fitting machine having, in combination, a support for a shoe, holddown members arranged to engage the sole of a shoe carried by the support adjacent to the ends of the heel breast line of the sole, and a cutter formed and arranged to trim surplus material from and to bevel the periphery of the heel-seat portion of the sole. 95 100

63. A heel-seat fitting machine having, in combination, a support for a shoe, holddown members arranged to engage the sole of a shoe carried by the support at the central portion of its heel-seat and adjacent to the ends of its heel breast line, a cutter mounted for movement transversely across the sole of the shoe from one edge of the sole to the other substantially at its heel breast line to form a heel breast receiving abutment in the sole, and a cutter formed and arranged to trim surplus material from and to bevel the periphery of the heel seat portion of the sole. 105 110

64. A heel-seat fitting machine having, in combination, a cutter, means for moving the cutter peripherally of the heel-seat portion of the sole of a shoe to trim surplus material therefrom, a holddown member adjacent to and movable with the cutter formed and arranged to engage and ride over the margin of the sole of a shoe as the cutter is brought into trimming relation to the sole and to press the sole against adjacent parts of the shoe so that the cutter can operate effectively upon a shoe the heel-seat portion of the sole 120 125 of which is unattached without danger of displacing the sole relatively to the remainder of the shoe.

65. A heel-seat fitting machine having, in combination, a support for a shoe, means for 130

trimming surplus material from the periphery of the heel-seat portion of the sole of a shoe carried by the support, and means for varying the position of the shoe transversely in the machine according to whether the shoe is a right or a left shoe.

66. A heel-seat fitting machine having, in combination, a support for a shoe, a cutter arranged to trim surplus material from the periphery of the heel-seat portion of the sole of a shoe carried by the support, a back gage arranged to position the shoe on the support longitudinally of the shoe, and means for varying the transverse positioning of the shoe on the support according to whether the shoe is a right or a left shoe.

67. A heel-seat fitting machine having, in combination, a support for a shoe, means for trimming surplus material from the periphery of the heel-seat portion of the sole of the shoe, a cutter movable transversely across the sole of the shoe at the heel breast line thereof, from one edge of the sole to the other, to form a heel breast receiving abutment in the sole, a back gage arranged to position the shoe lengthwise on the support relatively to the trimming means, and a pair of side gages engaging the upper of the shoe adjacent to its sole in the vicinity of the heel breast line of the sole to position the shoe transversely in the machine.

68. A heel-seat fitting machine having, in combination, a support for a shoe, a cutter movable peripherally of the heel-seat portion of the sole of a shoe carried by the support to trim surplus material therefrom, a back gage arranged to position the shoe lengthwise, a pair of side gages arranged to engage the shoe in the vicinity of the heel breast line, and means for moving the side gages transversely of the shoe, both in the same direction, to vary the transverse positioning of the shoe on the support according to whether the shoe is a right or a left shoe.

69. A heel-seat fitting machine having, in combination, a support for a shoe, crease plates arranged to enter the rand crease of a shoe carried by the support, a cutter movable peripherally of the heel-seat portion of the sole of the shoe to trim surplus material therefrom, a pair of side gages carried by the crease plates and movable therewith toward the shoe to engage the shoe in the vicinity of its heel breast line and to position the shoe widthwise with respect to the path of movement of the cutter, and means for moving said gages widthwise of the shoe both in the same direction to vary the transverse positioning of the shoe relatively to the path of movement of the cutter according to whether the shoe to be operated upon is a right or a left shoe.

70. A heel-seat fitting machine having, in combination, a support for a shoe, a pair of crease plates arranged to enter the rand crease

of a shoe carried by the support, a cutter movable peripherally of the heel-seat portion of the sole of the shoe to trim surplus material therefrom, a pair of side gages carried by the crease plates and movable therewith toward and from the shoe, said gages being arranged to engage the shoe in the vicinity of its heel breast line and to position the shoe widthwise with respect to the path of movement of the cutter, a manually operable controller, and connections from said controller to said gages arranged to cause movement of said controller to move said gages widthwise of the shoe, both in the same direction, to vary the transverse positioning of the shoe relatively to the path of movement of the cutter according to whether the shoe to be operated upon is a right or a left shoe.

71. A heel-seat fitting machine having, in combination, means for positioning a shoe, a cutter having a curved cutting edge constructed and arranged to operate upon the rear portion of an undistorted sole of a shoe to form a reduced heel-seat portion thereof shaped to fit within a concave attaching face of a heel, means for forming heel-breast receiving abutments upon the sole, and power-operated means for moving the cutter peripherally of the heel-seat of the sole of a shoe positioned by said means, from one end of the heel-breast line of the sole rearwardly and then forwardly to the other end of the heel-breast line, to trim surplus material from the periphery of the heel-seat portion of the sole.

72. A heel-seat fitting machine having, in combination, a support for a shoe, a cutter carried thereby and having a curved cutting edge constructed and arranged to operate upon the rear portion of an undistorted sole of a shoe to form a reduced heel-seat portion thereof shaped to fit within a concave attaching face of a heel, means for forming heel-breast receiving abutments upon the sole, and power-operated means for moving the cutter carrier and the cutter peripherally of the heel-seat of the sole of a shoe carried by the support from one end of the heel-breast line rearwardly and then forwardly to the other end of the heel-breast line, to trim surplus material from and to bevel the periphery of the heel-seat portion of the sole.

73. A heel-seat fitting machine having, in combination, a support for a shoe, a cutter having a single cutting edge, and means for continuously moving the cutter transversely across the sole of the shoe carried by the support in the same general direction from one edge of the sole to the other substantially at its heel-breast line in a curved path the end portions of which correspond to the transverse curvature of corresponding portions of a heel breast to cause the cutter to form a heel-breast receiving abutment in the sole of the shoe.

74. A heel-seat fitting machine having, in combination, a support for a shoe, a cutter having a single cutting edge, and means for continuously moving the cutter transversely across the sole of the shoe carried by the support in the same general direction from one edge of the sole to the other substantially at its heel-breast line in a path curved transversely of the heel and the end portions of which correspond to the transverse curvature of corresponding portions of the heel breast to cause the cutter to form a heel-breast receiving abutment consisting of two portions having substantial surface areas separated by the central part of the heel-seat portion of the sole which is substantially the full thickness of the sole. 70
75. A heel-seat fitting machine having, in combination, a support for a shoe, a cutter, rigid means extending peripherally of the sole of a shoe carried by the support and constructed and arranged to guide the cutter in a path and to prevent movement of the cutter out of said path, an eccentric, and connections between the eccentric and the cutter arranged as the eccentric is revolved to move the cutter under control of said means peripherally of the heel seat of the sole of the shoe carried by the support to trim surplus material therefrom. 75
76. A heel-seat fitting machine having, in combination, means for positioning a shoe, a cutter mounted for continuous movement transversely across the sole of the shoe from one edge of the sole to the other substantially at its heel-breast line in a path the portions of which adjacent to the edges of the sole are inclined transversely of the shoe whereby the cutter will form a heel-breast receiving abutment in the sole of the shoe shaped to receive a transversely curved heel breast. 80
77. A heel-seat fitting machine having, in combination, means for positioning a shoe, and a cutter having a single cutting edge mounted for continuous movement transversely across the sole of the shoe from one edge of the sole to the other substantially at its heel-breast line in a path curved transversely of the sole to form in the sole a heel-breast receiving abutment which corresponds to the transverse curvature of a heel breast. 85
78. A heel-seat fitting machine having, in combination, means for positioning a shoe, and a cutter mounted for progressive movement transversely across the sole of the shoe from one edge of the sole to the other substantially at its heel-breast line in a path curved transversely of the sole to cause the cutter to form a heel-breast receiving abutment corresponding to the transverse curvature of a heel breast and consisting of two portions each having considerable surface area and separated from the other by the central part of the heel-seat portion of the sole which is substantially the full thickness of the sole. 90
79. A heel-seat fitting machine having, in combination, a support for a shoe, a cutter, rigid means extending peripherally of the sole of a shoe carried by the support and constructed and arranged to guide the cutter in a path and to prevent movement of the cutter out of said path, an eccentric, and connections between the eccentric and the cutter arranged as the eccentric is revolved to move the cutter under control of said means peripherally of the heel seat of the sole of the shoe carried by the support to trim surplus material therefrom. 95
80. A heel-seat fitting machine having, in combination, a cutter, means for guiding the cutter peripherally of the heel-seat portion of the sole of a shoe, an eccentric, means for causing the eccentric to operate through a part of a revolution and then to come to rest, an eccentric strap surrounding the eccentric and connected to the cutter, said strap being arranged to cause the cutter to operate about the periphery of the heel-seat portion of the sole from one end of the heel-breast line thereof around the rear of the heel seat and then forwardly to the other end of the heel-breast line as the eccentric revolves and then to come to rest, and means controlled by the shoe for varying the degree of revolution of the eccentric. 100

CERTIFICATE OF CORRECTION.

Patent No. 1,834,083.

Granted December 1, 1931, to

HARRIE A. BALLARD.

It is hereby certified that error appears in the printed specification of the above numbered patent requiring correction as follows: Page 15, line 93, claim 27, for the word "carried" read curved; page 16, line 53, claim 34, for "of" second occurrence read to; and that the said Letters Patent should be read with these corrections therein that the same may conform to the record of the case in the Patent Office.

Signed and sealed this 14th day of June, A. D. 1932.

(Seal)

M. J. Moore,
Acting Commissioner of Patents.
